(57) **CLAIM**

The ornamental design for a cell capture system, as shown and described.

DESCRIPTION

FIG. 1 is a top perspective view of a cell capture system;
FIG. 2 is a side view of the cell capture system;
FIG. 3 is a top view of the cell capture system;
FIG. 4 is a bottom view of the cell capture system;
FIG. 5 is a cross-sectional view of the cell capture system;
and,
FIG. 6 is a bottom perspective view of the cell capture system.
The broken lines shown in the drawings of a cell capture system are for illustrative purposes only and form no part of the claimed design.
